REINFORCEMENT FOR CONTACT MEMBERS

John W. Samzelius, Pittsburgh, Pa., assignor to Westinghouse Electric & Manufacturing Company, East Pittsburgh, Pa., a corporation of Pennsylvania

Application July 16, 1938, Serial No. 219,516

6 Claims. (Cl. 200—166)

My invention relates, generally, to electrical contact members and, more particularly, to contact members or switch jaws designed for use with knife blade switches and fuses of the knife blade type.

For certain applications, it is desirable to supplement the inherent pressure of the jaws with auxiliary pressure producing or reinforcing means in order to increase the contact pressure between the current conducting parts. Furthermore, by providing auxiliary reinforcing means, the jaws may be made from copper without the danger of the jaw becoming distorted to the extent of losing its resiliency. The use of copper jaws is desirable because of its high conductivity and relative cheapness as compared with other materials. Heretofore, considerable difficulty has been experienced in satisfactorily securing the auxiliary reinforcing means in position on the contact members.

An object of the present invention, generally stated, is to provide a reinforced contact member which shall be simple and efficient in operation and which may be readily and economically manufactured and installed.

A more specific object of the invention is to provide a reinforcing member for a flexible jaw which may be removed readily from the jaw.

Another object of the invention is to provide a means for retaining resilient reinforcing members in position on contact jaws which will permit easy adjustment of the spring tension on the jaws.

Other objects of the invention will be explained fully hereinafter or will be apparent to those skilled in the art.

In accordance with one embodiment of the present invention, the spring reinforcing members for a switch or fuse jaw are retained in position by a locking piece of such a shape that it may be readily inserted in the reinforcing members and the jaw members through openings in these members and then releasably held in the locking position in which it engages the reinforcing members.

For a fuller understanding of the nature and objects of the invention, reference may be had to the following detailed description, taken in conjunction with the accompanying drawing, in which:

Figure 1 is a view, partially in end elevation and partially in section, of a reinforced jaw constructed in accordance with my invention;

Fig. 2 is a view, in side elevation, of one of the reinforcing members;

Fig. 3 is a view, in plan, of a locking member;

Fig. 4 is a view, in plan, of a filler member which is utilized to retain the locking member in the locked position;

Fig. 5 is a view, partially in end elevation and

partially in section, of a modification of the invention;

Fig. 6 is a view, in side elevation, of one of the reinforcing members utilized in the modified structure shown in Fig. 5;

Fig. 7 is a view in side elevation of one of the locking plates for the modified structure;

Fig. 8 is a view in plan of a pair of the locking plates, and

Fig. 9 is a view, in plan, of a pair of the locking plates with a tool for inserting the plates through the openings in the reinforcing members and the switch jaw.

Referring now to the drawing, and particularly to Fig. 1, the structure shown therein comprises a jaw 10, which is of substantially a U-shape, having an enlarged base portion 11, suitable for securing to a base plate (not shown), and a pair of spaced fingers 12 for engaging the blade of a knife switch or a fuse of the knife-blade type (not shown). As explained hereinbefore, the jaw 10 is preferably made from copper, although other suitable materials may be utilized if desired.

In order to increase the contact pressure between the fingers 12 and the switch blade, a reinforcing member or spring 13 is provided for each one of the fingers 12. The reinforcing members 13 are preferably made from spring steel, or other suitable material, having a high resiliency. As shown in Fig. 1, they are so shaped at the bottom that they conform with the shoulders 14 of the jaw 10. Each reinforcing member 13 is provided with an inverted T-shaped opening 15 as shown in Fig. 2. If desired, the opening 15 may be made with the top of the T disposed uppermost instead of inverted.

The T-shaped openings 15 are provided for the purpose of admitting a locking piece 16, having enlarged ends or heads 17 as shown in Fig. 3, and a filler piece 18 that prevents the locking piece 16 from dropping down into the wide portion of the T-shaped hole in the spring 13 when assembled, as shown in Fig. 1. The locking piece 16 is preferably made from cold-rolled sheet steel, spring steel or other suitable material by a punching operation. The filler piece 18 is likewise a punching from any soft and durable steel that permits the ends to be bent over and thus held in place, as shown in Fig. 1. The one end of the filler piece is preferably bent at 19, as shown in Fig. 4, before the piece is inserted in the openings 15.

It is apparent that the wide portion of the T-shaped opening 15 must be large enough to admit the head 17 of the locking piece 16. It is also apparent that the narrow portion of the hole 15 must be slightly larger than the body of the locking piece 16 but smaller than the head 17 in order that the shoulders of the locking piece 16

will engage the spring 13 when the locking piece is raised into the narrow portion of the opening 15.

In order to simplify the tools required to perform the punching operations, the holes through the copper fingers 12 should be made rectangular in shape and a size corresponding to the maximum dimensions of the T-shaped holes in the springs 13. The location of the holes should be such that the locking piece 16 serves as a stop for the fuse or switch blade when inserted between the fingers 12.

When assembling the springs, the only tool required is a simple fixture or a pair of pliers to compress the springs 13 while the locking piece 16 and the filler piece 18 are being inserted through the springs 13 and the fingers 12 of the jaw 10. After the members are assembled in their proper positions, the one end of the filler 20 piece may be bent over easily with a screw driver or a hammer to retain the filler piece in position.

If it is desired to remove the springs in order to refinish the contact surfaces of the fingers after they have been in service, this may be done 25 easily by utilizing a pair of pliers to straighten out the filler piece and then compress the springs 13 while the filler piece and the locking piece are being removed. Also, adjustment of the spring tension can be made easily at any time in the field 30 by inserting U-shaped washers of a desired thickness between the heads of the locking piece 16 and the springs 13.

In the modification of the invention shown in Figs. 5 to 9, inclusive, in which similar parts are 35 designated by the same reference character as in Figs. 1 to 4, inclusive, two locking pieces are utilized instead of one locking piece and one filler piece. The locking pieces are made from curved spring steel, as shown in Fig. 8. They 40 may be inserted edgewise through the spring members in order that the high edges will serve as a stop for the fuse or switch blade.

As shown in Fig. 6, the opening 15 is widest at the center and narrow at each side, thereby providing shoulders for the heads of both locking pieces 16. The assembly in this case is easily made by inserting one end of each locking piece in a small block 21, as shown in Fig. 9. The free ends are then pinched together with a pair 45 of pliers and the block inserted through the spring and jaw assembly, the springs being compressed in an assembly fixture or by means of another pair of pliers. Releasing the pliers which hold one end of the locking pieces and removing 50 the block from the other end will permit the curved locking pieces to engage the springs and keep them under the proper tension as determined by the length of the locking pieces. The two locking pieces are identical and can be 55 punched and formed cold from spring steel without annealing or heat treatment.

From the foregoing description, it is apparent that I have provided a contact structure which may be manufactured cheaply and may be readily assembled. Furthermore, the locking members which I have provided are of a durable construction and will, therefore, stand the severe vibration and rough usage to which switch and fuse structures are frequently subjected. The 65 structure may be easily disassembled and reassembled in the field if desired, thereby facilitating the repairing or renewing of worn parts.

Since numerous changes may be made in the above-described construction, and different em-

bodiments of the invention may be made without departing from the spirit and scope thereof, it is intended that all matter contained in the foregoing description or shown in the accompanying drawing shall be interpreted as illustrative and not in a limiting sense.

I claim as my invention:

1. The combination with a jaw having a base and spaced resilient fingers for engaging a movable member therebetween, of a spring for reinforcing each of said fingers, a removable locking piece for retaining the springs in position on the fingers, and a removable member coextensive with said locking piece for releasably retaining the locking piece in position.

2. The combination with a jaw having a base and a pair of spaced resilient fingers for engaging a movable member therebetween, of a pair of oppositely disposed springs for reinforcing said fingers, a removable locking piece for engaging both of said springs for releasably retaining the springs in position on the fingers, and a removable member coextensive with said locking piece for releasably retaining the locking piece in position.

3. The combination with a jaw having a base and a pair of spaced resilient fingers for engaging a movable member therebetween, of a pair of oppositely disposed springs for reinforcing said fingers, each of said springs having an opening therein with a restricted portion, a removable locking piece disposed in the restricted portion of said opening and having enlarged heads disposed to engage both of said springs for releasably retaining the springs in position on the fingers, and means for retaining the locking piece in the restricted portion of said opening.

4. The combination with a jaw having a base and a pair of spaced resilient fingers for engaging a movable member therebetween, of a pair of oppositely disposed springs for reinforcing said fingers, each of said springs having an opening therein with a restricted portion, a removable locking piece disposed in the restricted portion of said opening to engage both of said 45 springs for releasably retaining the springs in position on the fingers, and a removable member for releasably retaining the locking piece in the restricted portion of said opening.

5. The combination with a jaw having a base and a pair of spaced resilient fingers for engaging a movable member therebetween, of a pair of oppositely disposed springs for reinforcing said fingers, each of said springs having a T-shaped opening therein, a removable locking piece disposed in the narrow portion of said opening to engage both of said springs for releasably retaining the springs in position on the fingers, and a removable filler piece disposed in the wide portion of said opening to retain the locking piece in said narrow portion.

6. The combination with a jaw having a base and a pair of spaced resilient fingers for engaging a movable member therebetween, of a pair of oppositely disposed springs for reinforcing said fingers, each of said springs having an opening therein with restricted portions, and a pair of removable locking pieces disposed in the restricted portions of said opening to engage both of said springs for releasably retaining the springs in position on the fingers, said locking pieces being so disposed in said openings that they retain each other in said restricted portions.

JOHN W. SAMZELIUS.
